CIGARETTE PACKAGE AND MATCH BOOK HOLDER

Charles C. Baldwin, St. Louis, Mo.

Application September 23, 1938, Serial No. 231,445

8 Claims. (Cl. 206—48)

This invention relates to a combined cigarette package container and match book holder, and it is one object of the invention to provide a device of this character of such construction that a pack of cigarettes may be enclosed therein and a book of matches mounted externally of the package container in such position that a match may be easily removed and ignited.

Another object of the invention is to provide a combined cigarette package container and match book holder of such formation that they may be very easily disposed about a pack of cigarettes and prevent the cigarettes from being crushed when carried in a person's pocket and also constitute a shield serving to prevent cigarettes from accidentally slipping out of a pack and also prevent exposed end portions of cigarettes in an opened pack from becoming contaminated.

It is another object of the invention to provide a device of this character which will not only serve to prevent crushing of cigarettes and contamination thereof but also constitute means for preventing tobacco sifting from cigarettes in an open pack and accumulating in a pocket or hand bag.

Another object of the invention is to provide a combined container for a pack of cigarettes and holder for a book of matches, this device being formed from a single blank of cardboard or of light sheet material folded to assume the desired outline and secured in the folded condition by a tongue engaged through a slot.

It is another object of the invention to so apply a book of matches to the container that accidental displacement of the tongue which holds the blank in its folded or container-forming condition will be prevented.

Another object of the invention is to provide a device of this character which may serve not only as a shield and container for a pack of cigarettes but also as an advertising medium.

Another object of the invention is to provide a device of this character which can be stamped from cardboard and very cheaply manufactured and sold at such a price that it may be supplied to a purchaser without additional cost when used as an advertising medium.

The invention is illustrated in the accompanying drawings, wherein:

Figure 1 is a perspective view showing a container and match book holder of the improved construction applied to a pack of cigarettes and carrying a book of matches, the pack of cigarettes being partially displaced from within the container in order that a cigarette may be removed,

Figure 2 is a perspective view of the container before being applied to a pack of cigarettes or having a book of matches applied to it,

Figure 3 is a sectional view taken transversely through the container along the line 3—3 of Figure 2,

Figure 4 is a fragmentary sectional view taken vertically through the lower portion of the container along the line 4—4 of Figure 2,

Figure 5 is a view of the blank from which the container is formed,

Figure 6 is a perspective view of a modified form of container,

Figure 7 is a vertical sectional view taken along the line 7—7 of Figure 6 and indicating by dotted lines the manner in which a book of matches is applied thereto.

Figure 8 is a sectional view taken transversely through the container along the line 8—8 of Figure 6,

Figure 9 is a view of the blank from which the container of Figure 6 is formed,

Figure 10 is a perspective view of another modified form of container of such construction that after a pack of cigarettes has been placed in the container a corner portion of the wrapper may be easily torn away along edges of a corner recess and cigarettes then removed from a pack without partially dislodging the pack of cigarettes from the container,

Figure 11 is a view of the blank from which the container of Figure 10 is formed,

Figure 12 is a perspective view of another form of container wherein the recess for permitting tearing the wrapper and forming an opening for permitting removal of cigarettes without dislodging a pack therein is located intermediate the width of the front wall instead of at a corner of the container,

Figure 13 is a view of the blank from which the container of Figure 12 is formed, and

Figure 14 is a view illustrating a container having its front wall formed with an opening for disclosing the portion of the cigarette package carrying the name thereof, there being also advertising matter printed upon the outer face of the wall of the container through which the opening is formed.

The container, shown in perspective in Figures 1 and 2, is stamped from the blank shown in Figure 5. This blank, which is indicated in general by the numeral 1, consists of a substantially rectangular strip of sheet material, such as cardboard, and is scored to provide fold lines 2, along which the blank is folded to form the

top wall 3 and front and rear walls 4 and 5. The blank is also scored to provide fold lines 6 and 7 along which the blank is folded to form a bottom wall 8, and a flap 9 which is preferably disposed in overlapping relation to the lower end portion of the rear wall 5 when the blank is folded to form the container but may be disposed under the rear wall if so desired. A transversely extending tongue 10 is formed by cutting a recess or slit 11 in the flap 9, and when this tongue is engaged through the slit 12 formed vertically or longitudinally in the inner wall 5, the flap will be held in overlapping relation to the lower portion of the rear wall and maintain the container in its set up position for use. The container is of such dimension that it will snugly receive a pack of cigarettes 13, and since the container is open at its opposite sides, the pack of cigarettes may be partially dislodged by applying pressure at one side thereof, as shown in Figure 1, and thus permit one of the cigarettes 14 to be withdrawn through the torn corner portion 15 of the wrapper for the cigarettes. The pack of cigarettes may then be thrust back into place within the container, and since the container is formed of relatively stiff material, it will constitute a shield and prevent crushing of the cigarettes when placed in a person's pocket. The fact that the torn corner portion 15 of the pack of cigarettes will be disposed under the top wall 3 of the container will prevent the cigarettes from accidentally sliding out of the package and in addition prevent the exposed end portions of the cigarettes from becoming contaminated. Sifting of tobacco from ends of the cigarettes will also be prevented and accumulation of tobacco in a pocket or hand bag which would result therefrom eliminated. In order that a book of safety matches 16 may be applied to the container, the rear wall 5 is formed with a longitudinally extending slot 17. This slot extends longitudinally of the rear wall from adjacent the lower end thereof and is so located that, when the tongue 10 is engaged through the slit 12, the edge 18 of the flap 9 will be disposed flush with the inner side edge of the slot, and the edge 19 of the tongue 9 extends transversely of the wall 5 under the lower end of the slot. The backing or folder of the book of matches may, therefore, be passed through the slot and the portion 20 thereof forming a closure flap disposed in shielding relation to the matches with its free end engaged under the retainer flap 21 to which the striking substance is applied. The fact that the flap 9 has its corner portion cut away to provide the edges 18 and 19 permits the backing for the book of matches to be drawn through the slot 17 to such an extent that the flap 21 will be located inwardly from the adjacent side edge of the wall 5 or substantially flush therewith if so desired and thus permit packs of cigarettes having the container applied thereto to be stacked upon a shelf in a store in the usual manner. The exposed portion of the outer face of the wall 5 above the book of matches may be used for advertising purposes and advertising matter may also be printed or otherwise applied to the front wall 4 and the top and bottom walls 3 and 8. Therefore, the device will serve as an advertising medium as well as serving as a container for a pack of cigarettes and holder for a book of matches. As a book of matches will be applied to each container and the number of matches in a book corresponds to the number of

cigarettes in a pack of cigarettes, a supply of matches will be at hand for the cigarettes.

In Figure 6, there has been shown in perspective a modified form of container which is formed from the blank shown in Figure 9 and indicated in general by the numeral 22. In this embodiment of the invention, the blank is folded along the fold lines 23 and 24 to form the top and bottom 25 and 26 and front and rear walls 27 and 28 for the container together with the flap 29 extending upwardly from the bottom 26 for overlapping the lower end of the wall 28. The flap 29 has one corner portion cut to provide a transversely extending tongue 30 for engagement through the slit 31 to hold the flap in overlapping relation to the wall 28, and in order to accommodate a book of matches, the wall 28 is formed with an upper transversely extending slot 32 and a lower slot 33 which registers with the slot 34 of the flap. The backing or folder of the book of matches may, therefore, be threaded through the slots 34 and 33 and then extended upwardly and outwardly through the slot 32, as shown in Figure 7. The book of matches will thus serve to securely hold the flap in overlapping relation to the wall 28 and prevent the tongue 30 from accidentally slipping out of the slit 31, and when the closure flap of the book of matches is engaged under the companion flap carrying the striking substance, the matches in the book will be enclosed and shielded from accidental ignition. The end portion of the blank forming the wall 28 is provided with a side extension 35 which is folded along the fold line 36 and the line 37 to form a side wall 38 for the container carrying a tongue or lip 39 which extends inwardly against the inner face of the wall 27. Therefore, one side of the container will be closed but the container will be open at its other side, and when a pack of cigarettes is enclosed in the container, pressure may be applied to the side wall 38 adjacent its tongue 39 to partially eject the pack of cigarettes through the open side of the container and permit removal of a cigarette through a torn end portion of the top of the wrapper of the pack of cigarettes. In view of the fact that the container is closed at one side by the wall 38, there will be provided an additional surface for advertising purposes and there will be less likelihood of tobacco sifting from the cigarettes and into a person's pocket.

Another modified form of container has been shown in perspective in Figure 10, and this container is formed from the blank shown in Figure 11. This blank 40 is somewhat similar to the blank 22 as it is formed with a side extension 41. The blank is folded along the transversely extending fold lines 42 and 43 to form the front and rear walls 44 and 45 and top and bottom walls 46 and 47 together with the flap 48 which extends upwardly from the bottom wall 47 for overlapping engagement with the lower portion of the wall 45. The side extension 41 is folded along the scored line 49 to form a side wall 50 and the outer side edge portion of the extension is folded along the scored line 51 to provide a tongue or lip 52 which extends inwardly from the side wall 50 for engagement with the inner surface of the wall 44. This side of the container will thus be closed by a movable side wall. The lower portion of the side extension 41 and adjoining portion of the main body of the blank are cut to form a recess 53, and when the side extension is folded to form the side wall 50, the recess forms a corner opening through which an upper corner

portion of a pack of cigarettes P will be exposed when housed in the container. The type of cigarette pack for which this container is intended has the seam of its outer cup-wrapper P' extending along an end wall adjacent one side edge thereof and the inner wrapper P'' has its overlapped side edges disposed under the said side wall of the cup wrapper. It will thus be seen that the exposed upper portion of the cup wrapper P' may be grasped at the seam and torn towards the right in Figure 1 along edges of the recess and the remainder of the exposed portion of this wrapper then torn towards the left along the edges of the recess. The inner wrapper P'' may then be grasped and torn towards the left of Figure 1 along the top P''' of the wrapper and along edges of the recess and upper portions of cigarettes will be exposed through the recess or opening. It is then merely necessary to grasp the flap 54 together with the corner portion of the top P''' of the inner wrapper and when the flap is turned upwardly along the line of scoring 55, the corner portion of the top of the wrapper will be torn loose and carried upwardly with it to expose upper ends of the cigarettes so that they may be easily grasped and withdrawn. The flap and the underlying corner portion of the top of the inner wrapper may then be swung downwardly to cover upper ends of the exposed cigarettes and act as a shield for them. The slit 56 through which the transversely extending tongue 57 of the flap is passed is of arcuate outline instead of straight cut, and in order that the backing for the book of matches may be passed through the wall 45, there has been provided a slit 58 which is U-shaped and has its arm formed with extensions 59 extending longitudinally of the wall and provided with deflected ends 60. By so cutting the slit, there will be provided a tongue 61 and the backing or holder for the book of matches can be very easily passed inwardly through the slit to mount the book of matches transversely of the container.

The container shown in perspective in Figure 12 is open at both sides the same as the container illustrated in Figure 1 and is formed from the blank 61 shown in Figure 13. This blank is substantially oblong in shape and is folded along the transversely extending scored lines 62 and 63 to form the front and rear walls 64 and 65 and the top and bottom walls 66 and 67 together with the flap 68 which extends upwardly from the bottom 67 in overlapping relation to the wall 65 where it is held by the transversely extending tongue 69 passed through the V-shaped slit 70 cut in the lower portion of the wall 65. A transversely extending slot 71 is cut in the flap to register with the cut-out or recess 72 formed at the lower end of the wall 65, and attention is called to the fact that the cut-out or recess has side extensions 73 so that, when the backing or folder for a book of matches is passed inwardly through the registering slots and recess or cut-out 72, the folder will have inter-locking engagement with the lower end portion of the wall 45. After the folder or backing of the book of matches has been passed inwardly, it is then passed outwardly through the slit 74 extending transversely of the wall 65 and may then be brought downwardly into enclosing relation to the matches of the book which will be disposed externally of the container. The intermediate portion of the slit is U-shaped, as shown at 75, to form a tongue 76 constituting means to facilitate outward movement of the backing through the slit 74, and 75

ends of the slit are directed laterally longitudinally of the wall 65, as shown at 77, so that, when the backing of the book of matches is passed through the slit, tearing an extension of the slit 5 through the side edges of the wall 65 will be prevented. An opening 78 is formed in the upper end of the wall 65 intermediate the width thereof to expose a portion of a pack of cigarettes having the seams or overlapped edge portions of its cup wrapper P' and inner wrapper P'', extending midway the width of its rear wall, and the upper wall 66 of the container is cut along the diagonally extending line 79 to form a flap 80 which is to be bent upwardly along the line of scoring 81. 10 In this embodiment of the invention the pack of cigarettes is placed into the container through either side with the seam of the cup wrapper P' facing the wall 65 and the exposed upper portion of the cup wrapper grasped and pulled towards the right so that it will be torn from the top P''' and along edges of the opening 78, the remainder of the exposed portion of the cup wrapper being then torn towards the left from the top and along edges of the opening. The overlapping portion of the inner wrapper P'' is then torn towards the left along edges of the opening and the cigarettes will be exposed so that, when the flap 80 is grasped with the underlying portion of the top P'' and bent upwardly and the upwardly bent portion of the top torn loose, cigarettes may be easily removed from the pack. The flap and the underlying portion of the top P''' may then be returned to a lowered position for shielding the upper ends of the cigarettes. It will thus be seen that in this embodiment of the invention as well as that illustrated in Figure 10, it is not necessary to partially eject a pack of cigarettes from the container in order to remove cigarettes therefrom.

Instead of merely printing advertising matter upon the walls of the container, provision may be made for effecting a double or combination advertisement. Such an arrangement is illustrated in Figure 14 wherein the front wall 82 of the container 83 is formed with an opening 84 through which the portion of the pack of cigarettes 85 bearing the name thereof is displayed when the pack of cigarettes is enclosed in the container. While the opening 84 has been shown at the center of the wall 82, it will be understood that it may be otherwise located in case the disposition of the name upon the pack of cigarettes necessitates such a change. Above the opening 84 the wall 82 has printed thereon advertising matter, as shown at 86, and below the opening 84 advertising matter 87 which is companion to the advertising matter 86 is printed upon the wall. In the present instance, the advertising matter 86 consists of the words "Doe's Soda and" and the advertising matter 87 consists of "A Hit Combination." When the advertising slogan formed by the advertising matter 86 and 87 is considered in connection with the name of the cigarettes displayed through the opening 84, a slogan constituting a boost for the particular product printed upon the container and the make of cigarettes displayed through the opening 84 will be produced. It will thus be seen that the two companies which do not compete with each other could combine their advertising in a very effective manner or one company selling products in addition to cigarettes could very effectively combine advertising for both products. If so desired, the opening 84 may be cut in the shape of the trade-mark of

the product named at the top of the wall 82 or in the shape of the product or its container and more effectively call attention to the advertising matter. It will also be obvious that, if so desired, the advertising matter 86 and 87 shown upon the wall of the container in Figure 14 may be omitted and the opening merely serve to disclose the name of the cigarettes.

Having thus described the invention, what is claimed as new is:

1. A cigarette package container and match holder comprising a blank of sheet material folded to form a container adapted to receive a pack of cigarettes, one end portion of the blank forming a wall for the container and the other end portion of the blank forming a flap overlapping the lower end portion of said wall and formed with a transversely extending tongue engaging through a slit in the wall to releasably secure the flap to the wall, and said wall having a portion cut to form a slit having a U-shaped intermediate portion defining a tongue whereby the folder of a book of matches may be passed through the U-shaped slit and mounted against the outer face of the wall.

2. A cigarette package container and match holder comprising a blank of sheet material folded to form a container having a top and bottom and front and rear walls and a flap extending upwardly from the bottom in overlapping relation to one wall, the said wall being provided with a side extension folded to form a side wall for the container terminating in an inwardly extending lip along its free edge disposed against the other wall of the container, said flap being formed with a transversely extending tongue and the first-mentioned wall being formed with a slit to receive the tongue and being slitted to receive the folder of a book of matches whereby the book of matches may be removably secured against the said wall with a portion overlapping the flap to assist in holding the flap in engagement with the wall.

3. A cigarette package container and match holder comprising a blank of sheet material folded to form a container having a top and bottom and front and rear walls and a flap extending from the bottom in overlapping relation to the lower portion of one wall, said flap being formed with a transversely extending tongue engaged through a slit formed in the same wall to releasably hold the flap in engagement therewith, the said wall being formed with a side extension bent to form a side wall having a marginal portion folded inwardly, one wall of the container being cut to form an opening for exposing a portion of a pack of cigarettes in the container, and the top of the container being formed with a flap movable to a raised position whereby cigarettes may be withdrawn from a package in the container when the portion of the wrapper of the package exposed through the opening is torn away.

4. A cigarette package container and match holder comprising a blank of sheet material folded to form a container having a top and bottom and front and rear walls and a flap extending upwardly from the bottom in overlapping relation to the lower end portion of the rear wall, said flap being formed with a transversely extending tongue for engaging through a slit formed in the rear wall and securing the flap, said rear wall being slitted whereby the folder of a book of matches may be threaded through

the wall and secured against the same with a portion overlapping the flap, said rear wall having a lateral extension at one side folded to provide a side wall for the container, the upper portion of the side wall and the adjacent upper corner portion of the rear wall being cut-away to provide an opening for exposing a corner portion of a pack of cigarettes placed in the container, and the top of the container having a corner portion over the cut-out of the side wall and rear wall foldable upwardly out of covering relation to the exposed corner portion of the pack of cigarettes whereby cigarettes may be removed when the wrapper of the pack of cigarettes is torn from the exposed portion thereof.

5. A cigarette package container and match holder comprising a blank of sheet material folded to form a container adapted to receive a pack of cigarettes and having a top and bottom and front and rear walls and a flap extending upwardly from the bottom in overlapping relation to the lower portion of the rear wall, said flap being provided with a transversely extending tongue for engaging through a slit formed in the rear wall and releasably hold the flap in overlapping relation to the rear wall, said rear wall being slitted whereby the folder of a book of matches may be threaded through the wall and the book of matches mounted against the rear wall with a portion in covering relation to said flap, said rear wall having its upper portion formed with an opening intermediate its width for exposing a portion of a pack of cigarettes within the container, and the top of the container having a portion cut to form a flap movable to a raised position whereby cigarettes may be withdrawn when the portion of the wrapper exposed through the opening of the rear wall is torn away.

6. A cigarette holder comprising a container adapted to receive a pack of cigarettes and having a top and a bottom and front and rear walls and a side wall, said rear wall being slitted whereby the folder of a book of matches may be threaded through the wall and the book of matches mounted against the rear wall in position for use, an upper corner portion of the side wall and the adjacent upper portion of the rear wall being cut away to form an opening for exposing a corner portion of a pack of cigarettes placed in the container, the top of said container having a corner portion over the opening foldable upwardly to expose upper portions of the cigarettes whereby said cigarettes may be removed from the pack when the wrapper of the pack of cigarettes is torn from the exposed portion thereof.

7. A cigarette holder comprising a container adapted to receive a pack of cigarettes and having a top and a bottom and front and rear walls and a side wall, said rear wall being slitted whereby the folder of a book of matches may be threaded through the wall and the book of matches mounted against the rear wall in position for use, an upper corner portion of the side wall and the adjacent upper portion of the rear wall being cut away to form an opening for exposing a corner portion of a pack of cigarettes placed in the container whereby a pack of cigarettes having the seam of its cup wrapper and the overlap of its inner wrapper adjacent a corner thereof may have the exposed portion of its cup wrapper and its inner wrapper torn

away along edges of the opening to expose upper end portions of cigarettes in the pack, the top of the container having a corner portion over the cut out foldable upwardly together with a portion of the top of the inner wrapper to permit removal of the exposed cigarettes from the pack.

8. A cigarette holder comprising a container adapted to receive a pack of cigarettes and having a top and a bottom and front and rear walls and a side wall, said rear wall being slotted whereby the folder of a book of matches may be threaded through the wall and the book of matches mounted against the rear wall in position for use, an upper corner portion of the side wall and the adjacent upper portion of the rear wall being cut away to form an opening for exposing a corner portion of a pack of cigarettes placed in the container whereby a pack of cigarettes having the seam of its cup wrapper and the overlap of its inner wrapper adjacent 20

a corner thereof may have the exposed portion of its cup wrapper and its inner wrapper torn away along edges of the opening to expose end portions of cigarettes in the pack, an additional portion of the upper end of the rear wall being adapted to be torn away to form a continuation of the opening across the rear wall and expose the upper portion of a pack of cigarettes having the seam of its cup wrapper and the overlap of its inner wrapper intermediate the width of its rear wall and permit tearing away of exposed portions of the wrappers along edges of the opening to expose upper end portions of cigarettes in the pack, and the top of the container and the top of the inner wrapper of the pack of cigarettes being foldable upwardly over the opening to expose upper ends of the said cigarettes and permit removal thereof from the pack.

CHARLES C. BALDWIN.
